PRESSURE ACCUMULATOR

Lawrence D. Orser, Cedar Falls, Iowa, assignor to Chamberlain Corporation, Waterloo, Iowa, a corporation of Iowa

Application August 24, 1955, Serial No. 530,287

3 Claims. (Cl. 138—30)

This invention relates to a pressure accumulator or pressure tank, and more particularly to a pressure accumulator for holding liquid under pressure and capable of discharging substantially all of the liquid under pressure. Generally, the invention may be employed in connection with spraying apparatus, although other uses and purposes will be apparent to one skilled in the art.

Heretofore, in pressure accumulators, it has not been possible to expel substantially all of the liquid out of a pressure accumulator without supplying compressed air thereto for each batch of liquid. These accumulators, most frequently used with spraying apparatus and into which liquid to be sprayed is pumped from a supply tank, as heretofore used discharged the liquid with a steadily diminishing pressure ultimately reaching substantially zero. Thus, the last portion of the liquid would not be sprayed effectively unless the pressure was built up in the interim. This has caused a great inconvenience and loss of spraying time, thereby making the spraying operation more expensive and in most cases a two-man job.

Accordingly, it is an object of this invention to provide a pressure accumulator of simple and economical construction for dispensing liquid under pressure that is capable of dispensing substantially all of the liquid held thereby under pressure.

Another object of this invention resides in the provision of a pressure accumulator having means for facilitating the entering and exiting of liquid from the accumulator while always maintaining pressure in the accumulator so that substantially all of the liquid in the accumulator may be dispensed therefrom under a positive pressure of a predetermined minimum amount.

A further feature of this invention is in the provision of a pressure accumulator for use with spraying apparatus that decreases the amount of pumping in the spraying operation.

Another object of this invention is to provide a pressure accumulator for use in spraying apparatus, wherein the accumulator is initially supplied with a predetermined amount of compressed air before liquid is pumped into the accumulator, and having a float valve assembly for permitting the entering and exiting of the pumped liquid while preventing the escape of the compressed air.

A still further object of this invention is to provide a pressure accumulator for use with spraying apparatus and having a float valve, wherein the proper relationship between the liquid and air in the accumulator is maintained at all times, and the initial air in the accumulator is not mixed with the liquid so as to gradually escape from the tank.

While some of the more salient features, characteristics and advantages of the instant invention have been above pointed out, others will become apparent from the following disclosures, taken in conjunction with accompanying drawings, in which:

Figure 1 is an axial sectional view taken through a pressure accumulator constructed in accordance with the

2

principles of the invention, with some parts in elevation, and illustrating the float valve in closed position;

Figure 2 is a view similar to Figure 1, but illustrating the float valve in fully open position and a higher level of liquid in the accumulator; and

Figure 3 is an enlarged plan view of the perforated guide plate which assures movement of the float valve substantially along a linear path.

As shown on the drawing:

10 The pressure accumulator of the instant invention includes a pressure tank 10 constructed of any suitable pressure resisting material, preferably steel, and which may take any desired shape or configuration. In the instant case, the pressure tank 10 is cylindrical and provided with dome-shaped ends 11 and 12.

Compressed air is supplied to the tank 10 through a conventional air valve 13 mounted at the upper end 11. The air valve will, of course, allow compressed air to pass therethrough only in one direction, which is 20 into the tank 10. A pressure gauge 14 of any conventional type is also mounted at the upper end 11 of the tank 10 to indicate the pressure of the compressed air within the tank.

To prevent the loss of initially supplied compressed 25 air from the tank 10, a float valve assembly 15 is provided which coats with an inlet-outlet passageway 16 at the bottom end 12 of the tank.

An opening 17 of circular shape is disposed substantially centrally of the tank bottom 12. A disk-shaped 30 mounting plate 18 having an offset bore 18a is suitably secured around the opening 17 on the bottom 12 in any suitable manner, such as by welding. A second disk-shaped plate 19 underlies the plate 18 and is of substantially the same diametral size. The plates 18 and 19 are provided with a series of aligned annularly arranged tapped holes for receiving a plurality of stud bolts 20 for securing the plate 19 to the plate 18.

The plate 19 is centrally tapped to receive a nipple 21. The bottom end of the nipple is threaded received by 40 a cross fitting 22 which is closed at its opposite end by a nipple and cap assembly 23.

The cross fitting 22 is connected at one end to a conduit or hose 24 which leads from a liquid supply such as a conventional hand pump and open tank (not shown) 45 used in connection with spraying apparatus. Opposite the connection to the conduit 24, the cross fitting is connected to a discharge conduit or hose 25 which leads to a point of forced liquid discharge such as a spray head or nozzle (not shown) of any conventional type. Also while not shown, it will be understood that somewhere in the line 24 between the pump and the cross fitting 22, a check valve would be positioned to prevent the return flow of liquid to the pump.

At the upper end of the nipple 21, an annular shoulder 55 26 is provided with a beveled valve seat 26a. The valve seat coats with a spherical or ball member 27 of the float assembly which functions as a valve face, and is shown in the closed position in Figure 1. A float member 28 is suitably attached to the upper end of the spherical member 27. The float may be constructed of 60 any suitable type of material and may take the form of a hollow metal disk or block.

A guide rod 29 depends from the bottom of the ball member or spherical member 27 and is slidable through a centrally positioned aperture 30a in a perforated guide plate 30. The guide plate 30 is received within the opening of the cross fitting connecting to the nipple 21. The guide rod extends well below the disk 30 and carries an adjustable stop member 31 thereon which may be locked in position at a desirable position on the rod 29 to coat with the disk 30 in restricting the upward travel of the float valve assembly 15. It is seen that the guide

rod 29 maintains the ball member 27 in alignment with the valve seat 26a and permits only a substantially linear path of movement.

An adjustable pressure relief valve 32 is carried by the plates 18 and 19 and communicates with the inside of the tank 10 to prevent the pressure therein from rising above a predetermined amount.

In operation, the pressure tank 10 is given a charge of compressed air to a predetermined amount, say 50 pounds, and then fluid to be sprayed is pumped into the tank through the conduit 24 against the air pressure already therein. During the charging of the tank with compressed air, the float valve assembly 15 will take the position as seen in Figure 1 in closing the inlet-outlet 16. While fluid is shown in the very bottom of the tank 10 in Figure 1, it will be understood that initially no liquid will be present.

When the spray liquid is pumped into the pressure tank 10, the level of the liquid will rise above the float member 28 of the float valve assembly 15 to maintain the inlet-outlet 16 open as seen in Figure 2. The liquid obviously compresses the air to a considerably greater pressure, say 150 pounds, and the air will not mix with the liquid, but will remain in the upper portion of the tank as illustrated.

As indicated by the diagonal lines in the tank 10 above the liquid level in Figures 1 and 2, the greater number of lines in Figure 2 illustrate a greater pressure in the tank when charged with liquid.

During the spraying operation, when the liquid will be discharged through the conduit 25, the pressure of course, will gradually decrease, and as the level of the liquid falls below the top of the float member 28, the float valve assembly 15 will descend until the ball member 27 seats on the valve seat 26a. Thus, an extremely small amount of liquid may remain in the bottom of the tank, but there will also be a minimum of 50 pounds pressure remaining in the tank so that the last portion of the liquid discharged from the tank is effectively sprayed.

In view of the foregoing, it is seen that the float valve arrangement maintains a minimum pressure in the tank 10 while allowing substantially all of the spraying liquid to be discharged therefrom without further pumping operations. Also, it is seen that at all times a proper relationship between the spraying liquid and the compressed air is maintained, and the initial air in the accumulator does not mix with the liquid so as to gradually escape from the tank. Once charged with compressed air to the desired extent, the tank may be used repeatedly without loss of that initial charge.

It will be understood that modifications and variations may be effected without departing from the scope of the novel concepts of the present invention, but it is understood that this application is to be limited only by the scope of the appended claims.

I claim as my invention:

1. A pressure accumulator including a single chamber pressure tank for holding compressed air and liquid, said tank having an inlet for admitting compressed air thereto, a liquid inlet-outlet in the tank bottom, a conduit

outside said tank extending axially from said tank inlet-outlet leading to a liquid source and a liquid outlet, a valve seat provided on said inlet-outlet, and a valve assembly having a spherical member defining a valve face

5 for coacting with the valve seat, a float member connected to said spherical member and being within the confines of said tank, a guide rod extending downwardly from said spherical member in the confines of said conduit for guiding said member along a linear path, a guide plate in said conduit slidably receiving said guide rod, and an adjustable stop on said rod coacting with said plate to restrict the linear movement of said spherical member, said valve assembly permitting the entering and exiting of liquid and preventing the exiting of compressed air.

10 2. A pressure accumulator including a single chamber pressure tank for holding compressed air and liquid, said tank having an inlet for admitting compressed air thereto, a liquid inlet-outlet in the tank bottom, a valve seat provided on said inlet-outlet, and a valve assembly having a valve member defining a valve face coacting with the valve seat, a float member connected to said valve member and being within the confines of said tank, a guide rod extending downwardly from said valve member and outwardly of said tank, and means outside said tank slidably receiving said guide rod in axial alignment with said inlet-outlet for guiding said valve member along a linear path.

15 3. A pressure accumulator including a single chamber pressure tank for holding compressed air and liquid, said tank having an inlet for admitting compressed air thereto, a liquid inlet-outlet in the tank bottom, a valve seat provided on said inlet-outlet, and a valve assembly having a valve member defining a valve face coacting with the valve seat, a float member connected to said valve member and being within the confines of said tank, a guide rod extending downwardly from said valve member and outwardly of said tank, means outside said tank slidably receiving said guide rod and maintaining said guide rod in axial alignment with said inlet-outlet for guiding said valve member along a linear path, and an adjustable stop on said rod, said stop being disposed beneath said means slidably receiving said rod and coacting therewith to restrict the linear movement of said valve member, said valve assembly permitting the entering and exiting of liquid and preventing the exiting of compressed air.
